United States Patent Office

Des. 197,518
Patented Feb. 18, 1964

197,518

STORAGE BATTERY CASE

Andreas Karl Rohé, Königstein, Taunus, Germany,
assignor to Walter Glass, Northfield, Ill.

Filed June 21, 1963, Ser. No. 75,468

Term of patent 14 years

(Cl. D26—6)

Fig. 1.

Fig. 2.

Fig. 3.

Fig. 4.

FIG. 1 is a front elevational view of a storage battery case showing my new design, the rear being substantially a mirror image thereof;

FIG. 2 is a bottom plan view;

FIG. 3 is a top plan view; and

FIG. 4 is a right side elevational view, the left side being a mirror image thereof.

I claim:

The ornamental design for a storage battery case, as shown and described.
